UNITED STATES PATENT OFFICE.

FREDERICK W. HODGES, OF DETROIT, MICHIGAN, ASSIGNOR TO DETROIT LUBRICATOR COMPANY, OF DETROIT, MICHIGAN, A CORPORATION OF MICHIGAN.

VALVE.

1,161,861.

Specification of Letters Patent. Patented Nov. 30, 1915.

Application filed September 11, 1912. Serial No. 719,748.

To all whom it may concern:

Be it known that I, FREDERICK W. HODGES, a citizen of the United States of America, residing at Detroit, in the county of Wayne 5 and State of Michigan, have invented certain new and useful Improvements in Valves, of which the following is a specification, reference being had therein to the accompanying drawings.

The invention relates to valves more particularly designed for use in connection with vacuum steam heating systems and for similar purposes where the port opening of the valve is varied in accordance with its location in the system.

It is the object of the invention to obtain a construction in which adjustment can be readily made without dismounting the valve or changing the relation of parts employed 20 in its normal operation.

In the drawings: Figure 1 is a longitudinal section through the valve; Fig. 2 is a plan view thereof; and Fig. 3 is a section on line $x-x$.

A is the valve casing; B is the cap therefore, through which the valve stem C projects; D is an operating handle engaging the valve stem; E an indicator disk; and F a stop pin on the valve handle engaging a segmental slot G in said disk to limit the 30 normal turning of the stem. The valve H as shown is of the hollow plug type, and is provided with a port I adapted to register with a port J in the case A. These ports when in 35 registration open a passage from the main body of the case into a laterally extending nipple K to which the supply pipe is connected.

When a valve, such as described, is used 40 in a vacuum steam heating system it is desirable to vary the port opening according to the position of the valve in the system. It is also desirable to effect this adjustment without disconnecting the valve from the 45 system. This I have accomplished by an adjustable engagement between the plug and its operating stem permitting the former to be moved longitudinally within the central valve case. I have further provided a 50 means for effecting this adjustment without detaching the cap B of the case, and one which enables the operator to determine exactly the degree to which the ports are restricted.

55 In detail, the valve stem C is of a polygo-

nal cross section, and engages a correspondingly formed aperture in the plug H so as to rotate with the latter while permitting independent longitudinal movement. The plug H has a head portion L, which is provided with a fine screw thread engaging a corresponding longitudinal screw thread in the cap member B. This threaded engagement will cause a relative longitudinal adjustment of the stem and plug during the 60 rotation thereof, but the limited angular adjustment of the stem in opening and closing the port will cause but very slight longitudinal displacement of the plug. Whenever it is desired to change the port opening 65 of the valve the stop pin F is removed from its engagement with the segmental slot G which permits the continuous rotation of the handle D in either direction. Thus the operator is permitted to screw the plug upward or downward in the threaded cap B, and sufficient range of adjustment is provided to vary the port opening from full 70 opening to complete closure.

The plug H is preferably slotted longitudinally and has sufficient resiliency to adjust itself automatically to its cylindrical seat. The stem is packed to prevent leakage, preferably by forming a collar M thereon which bears against a packing ring N, 85 and the latter against a shoulder O on the cap. The end of the stem C has a threaded portion P which engages a nut Q.

R is a spring between the nut Q and a cup-shaped bearing S in the handle D, the arrangement being such that the stem is resiliently drawn outward to maintain a pressure of the collar M upon the packing N.

In the adjustment of the valve the operator, knowing the number of threads to the 95 inch, can effect any desired adjustment by a suitable number of turns of the handle, after which the stop pin F is replaced in engagement with the slots G, which will limit the angular movement of the stem. 100

It will be obvious that by having a stem for the valve which does not shift its position sidewise, that is a non-lifting stem, the packing for the stem is not affected by the adjustment of the valve to change its port 105 opening.

What I claim as my invention is:

1. The combination with a valve case, of a plug valve in said case, a stem for rotating said valve, a handle engaging the stem 110

for operating the valve, an adjustable stop member carried by the handle, an indicator disk mounted upon the case and formed with shoulders in the path of rotation of the stop member, normally limiting the angular motion of the handle, and means operable upon an adjustment of the stop member out of the path of said shoulders, and upon subsequent rotation of the handle, for adjusting the valve with respect to the stem and valve case to variably restrict the port opening of the valve.

2. The combination with a valve case of a rotary cylindrical, hollow plug-valve seated within said case, a recessed cap for said case, longitudinally threaded to engage a threaded portion of said plug, a stem having a polygonal portion engaging a corresponding aperture in the end of said plug, and a cylindrical portion engaging a bearing in said cap, a collar on said stem, a packing between said collar and said cap, a handle engaging said stem having a cupped portion surrounding the same, a spring within said cupped portion and a nut on the end of said stem forming a bearing for said spring.

3. The combination with a valve casing, a revoluble valve and a valve stem, the stem and casing being formed with coacting

shoulders, the stem being formed with a stud at its outer end, a packing interposed between said shoulders, a handle member engaging a polygonal portion of the stem exterior to the casing, a nut engaging said stud, and a spring compressed between the handle member and said nut, retaining the handle member in engagement with the polygonal portion of the stem and maintaining the packing pressed between said coacting shoulders.

4. The combination with a cylindrical valve member formed at one extremity with an exteriorly threaded head of a diameter greater than that of the valve proper, of a casing having a ported portion with which the valve proper has sliding engagement and having a threaded portion engaged by the valve head, and means for rotating the valve to open and close the same and to vary its maximum portage, the threaded portion of the casing receiving both the valve head and a portion of the valve proper in the position of maximum portage of the valve.

In testimony whereof I affix my signature in presence of two witnesses.

FREDERICK W. HODGES.
